UNITED STATES PATENT OFFICE.

CARL CARLSSON, OF STOCKHOLM, SWEDEN.

CARBURETOR FOR INTERNAL-COMBUSTION ENGINES.

Application filed April 23, 1925, Serial No. 25,286, and in Sweden February 21, 1925.

The present invention consists of a carburetor, or a device for intimately mixing liquid fuel with air, for internal combustion engines or the like, of such construction, 5 hereafter fully described, that it works satisfactorily as well with heavy combustible oils and gasoline as with alcohol and with a mixture of both, and has been found to work exceedingly well with all the said fuels. It 10 is so constructed as to disperse in the highest possible degree the combustible oils and to mix them most intimately with the air.

The invention is illustrated by way of example in the accompanying drawings, in 15 which—

Fig. 1 is a vertical section through the entire device, Fig. 2 a view from above of the piece (10 of Fig. 1), called the venturi, and Fig. 3 a longitudinal section of the 20 valve (the cock valve 9 of Fig. 1).

Referring to the Fig. 1, the device of the invention consists of a float chamber or receptacle for the fuel 1, a chiefly cylindrical casing 2, communicating with the float chamber 1 by means of an inlet 3, leading to a vertical channel 4 in the wall of the casing 2 and closed at its bottom by a screw stopper. From the side of this channel 4 another channel 5 branches out, running, generally horizontally, into the centre of the device and communicating with an upright nozzle 6, situated in the middle of the central cavity of the casing 2. This nozzle 6 is at its upper or outlet end provided with a choke-tube 7 in the shape of a hollow cylinder, whose walls are thickest at the middle and narrowing out towards both ends of the cylinder. This choke-tube 7 is fixed to the top of the nozzle 6 by means of thin brackets. 35 In the upper end of said channel 4 is provided another nozzle 8, opening into a valve 9, generally a cock valve, which communicates with an annular channel 11, cut out in the outer cylindrical surface of the venturi 10. The casing 2 has further an air inlet 13, conveniently on the side opposite to the float chamber, and at the top an outlet 14 for the mixture of air and fuel. This outlet is controlled by a throttle valve 15, 40 which by means of a rod 16 or some other known device is connected with the cock valve 9 in such manner, that both valves open and shut simultaneously. The cock valve 9 is generally cylindrical, Fig. 3, and 45 at one end partly cut out, 17, in order to

communicate, when in a certain position or when it is open, with the annular channel 11. The other end, 18, of this valve is open to let in air, and the cut out, 17, allows the entrance of the nozzle 8.

The construction of the device being thus fully described, it works in the following manner. The oil or other liquid fuel runs from the float chamber 1 through the outlet 3 into the channel 4. There it divides, part 60 of it passing through the channel 5 and the nozzle 6, being when leaving the latter finely dispersed by the air sucked in from the air inlet 13 through the cylindrical choke-tube 7 between the brackets. Another part of 65 the fuel in the channel 4 passes through the nozzle 8 into the valve 9 and, if this valve is open, that is with the cut out 17 turned to the right (in the Fig. 1), into the annular channel 11 together with air, sucked in through 70 the open end 18 of the valve 9. From there it is forced out through the openings 12 of the venturi 10. These openings preferably being widening outwards, from the annular chamber, the mixture of air and fuel is very 75 well mingled. This mixture is here met by the air from the inlet 13, having passed outside of the cylindrical choke-tube 7, and by the mixture of air and fuel coming from the nozzle 6. By this arrangement is effected 80 an exceedingly thorough and intimate mingling of the fuel and the air and at the same time a perfect evaporation of the liquid fuel, particularly well suited to the requirements of an internal combustion engine. 85

The invention is susceptible to various changes in its form, proportions, and minor details of construction, and the right is herein reserved to make such changes as properly fall within the scope of the appended claims.

Having described the invention, what I claim is:

1. A carburetor for mixing liquid fuel with air, consisting of a preferably chiefly cylindrical, hollow casing with an upright nozzle in its centre, and provided with an air inlet and an outlet, said nozzle communicating with a float chamber by means of a channel; the cavity of said hollow casing being narrowed around the outlet opening of said upright nozzle by means of a separate venturi; said channel from the float chamber to said upright nozzle branching out into a channel in the wall of the 100
- 105
- 110

said hollow casing, the last named channel opening by means of a nozzle into the interior of a hollow valve that controls a channel communicating with holes in the said venturi, said holes opening into the interior of the venturi.

2. A carburetor for mixing liquid fuel with air, consisting of a preferably chiefly cylindrical, hollow casing with an upright nozzle in its centre, and provided with an air inlet and an outlet, said nozzle communicating with a float chamber by means of a channel; the cavity of said hollow casing being narrowed around the outlet opening of said upright nozzle by means of a separate venturi; in combination with a choke-tube open at each end, and surrounding and fixed to the upper end of said upright nozzle and whose inside diameter is widening towards each end; said channel from the float chamber to said upright nozzle branching out into a channel in the wall of the said hollow casing, the last named channel opening by means of a nozzle into the interior of a hollow valve that controls a channel communicating with holes in the said venturi, said holes opening into the interior of the venturi.

3. A carburetor for mixing liquid fuel with air, consisting of a preferably chiefly cylindrical, hollow casing with an upright nozzle in its centre, and provided with an air inlet and an outlet, said nozzle communicating with a float chamber by means of a channel; the cavity of said hollow casing being narrowed around the outlet opening of said upright nozzle by means of a separate venturi; in combination with a choke-tube open at each end, and surrounding and fixed to the upper end of said upright nozzle and whose inside diameter is widening towards each end; said channel from the float chamber to said upright nozzle branching out into a channel in the wall of the said hollow casing, the last named channel opening by means of a nozzle into the interior of a hollow cylindrical cock valve that controls a channel leading to an annular channel in the said venturi by means of a cut-out in the wall of the valve, said annular channel communicating with holes in the said venturi, said holes opening into the interior of the venturi.

4. A carburetor, for mixing liquid fuel with air, consisting of a cylindrical, hollow casing with an upright nozzle in its centre, and provided with an air inlet and an outlet, said nozzle communicating by means of a

channel, with a float chamber, the cavity of said hollow casing being narrowed around the outlet opening of said upright nozzle by means of a separate venturi, in combination with a choke-tube in the shape of a hollow cylinder open at each end, surrounding and fixed to the upper end of said upright nozzle, the walls of said cylinder being thicker in the middle part and narrowing out towards each end, said channel from the float chamber to said upright nozzle branching out into a vertical channel in the wall of said hollow casing, said vertical channel opening, by means of a nozzle, into a cylindrical cock valve, this valve communicating, when open, with an annular channel in said venturi, said annular channel surrounding the top of said upright nozzle, said valve being provided with a cut-out for the communication with said annular channel and open to the outer air at its other end, said annular channel having a number of openings into the upper interior part of said venturi.

5. A carburetor for mixing liquid fuel with air, consisting of a preferably chiefly cylindrical, hollow casing with an upright nozzle in its centre, and provided with an air inlet and an outlet, said nozzle communicating by means of a channel, with a float chamber, the cavity of said hollow casing being narrowed around the outlet opening of said upright nozzle by means of a separate venturi, in combination with a choke-tube in the shape of a hollow cylinder open at each end, surrounding and fixed to the upper end of said upright nozzle, the walls of said cylinder being thicker in the middle part and narrowing out towards each end, said channel from the float chamber to said upright nozzle branching out into a vertical channel in the wall of said hollow casing, said vertical channel opening, by means of a nozzle into a cylindrical cock valve, this valve communicating, when open, with an annular channel in said venturi, said annular channel surrounding the top of said upright nozzle, said cock valve, provided with a cut-out for the communication with said annular channel and open to the outer air at its other end, said annular channel having a number of openings into the upper interior part of said venturi, said openings widening out from the annular channel.

In testimony whereof I have hereunto affixed my signature.

CARL CARLSSON
